UNITED STATES PATENT OFFICE.

CHARLES G. TROSIEN, OF PONTIAC, MICHIGAN, ASSIGNOR OF ONE-FOURTH TO MARY E. WELCH AND ONE-FOURTH TO ARTHUR PACK, BOTH OF PONTIAC, MICHIGAN.

DIAPHRAGM-HORN.

1,218,229.

Specification of Letters Patent.

Patented Mar. 6, 1917.

Application filed December 9, 1915. Serial No. 66,009.

To all whom it may concern:

Be it known that I, CHARLES G. TROSIEN, a citizen of the United States, residing at Pontiac, county of Oakland, State of Michigan, have invented a certain new and useful Improvement in Diaphragm-Horns, and declare the following to be a full, clear, and exact description of the same, such as will enable others skilled in the art to which it 5 pertains to make and use the same, reference being had to the accompanying drawings, which form a part of this specification.

This invention relates to a diaphragm horn arranged to be carried by the fan bracket of an automobile and actuated by a cam rotated by the fan pulley.

The object of this structure is to produce a horn actuated by one of the rapid moving parts of an automobile, and which requires 20 a minimum number of parts and occupies as small a compass as possible.

In the drawings,—

Figure 1 is a rear end view of the fan bracket, fan pulley, fan and the complete 25 horn structure, showing a part of the bell of the horn and diaphragm in section.

Fig. 2 is a side view of the same parts, the pulley belt and diaphragm actuator being partly in section.

30 *a* indicates the ordinary fan which is located behind the automobile radiator (not shown) to cool the internal combustion engine (not shown). *b* designates the fan bracket which is here shown as a separate 35 member from the engine casting but which will be referred to as the fan support. *c* indicates the shaft or bearing carried by the bracket or fan support and upon which the fan *a* and its pulley wheel *e* rotate. The 40 pulley wheel is provided with a hub *f* over which the actuator *g* may be tightly fitted so that the actuator and the pulley rotate together.

An arm *h* which will be termed the diaphragm-carrying arm, is here shown as 45 provided with a sleeve end which can be fastened to the fan shaft *c* by means of the set screw *i*, the idea being to have the diaphragm-carrying arm *h* secured to the bearing 50 that allows the rotation of the pulley and the fan and at the same time acts as a carrier for the same. The opposite end of the diaphragm-carrying arm *h* is bifurcated to pivotally support a link *j* that is 55 fastened to the diaphragm-holding shell *k*.

This diaphragm-holding shell *k* engages with the periphery of the diaphragm *l* and in conjunction with the flared inner end of the bell *m* holds the diaphragm. The center zone of the diaphragm is, therefore, free to 60 warp in and out at a very high rate of vibration when the serrated periphery of the actuator strikes the contact button *n* at the center of the diaphragm. A bolt *o* screws into the diaphragm-carrying arm *h* and 65 slidingly protrudes through the diaphragm-holding shell *k*. That end protruding through the diaphragm-holding shell is provided with a head to prevent the bolt from passing out of the shell. The coiled 70 spring *p* is interposed between the diaphragm-carrying arm *h* and the diaphragm-holding shell *k* and hence normally tends to force the diaphragm-holding shell and the diaphragm away from the diaphragm-carrying arm *h*, the said diaphragm-holding shell and diaphragm being free to pivot on 75 the pivotal connection between the link *j* and the diaphragm-carrying arm *h*. Of course the head of the bolt *o* limits the outward swing of the diaphragm-holding shell and the diaphragm, and this limit is so fixed as to just allow the button *n* to clear the 80 toothed periphery of the actuator *g*. On the side of the diaphragm-holding shell *k* 85 opposite the link *j* an ear *q* is provided, to which may be fastened a wire cord or other drafting appliance *r*, which may be passed through a Bowden tube *s* to a position within easy reach of the driver of the car. 90

Normally the contact button is kept out of contact with the toothed periphery of the actuator by means of the spring which swings the bell, diaphragm-holding shell and diaphragm outwardly just enough to 95 allow the button to clear the teeth of the actuator. It is desirable that the clearance be kept as small as possible so as to minimize the amount of pull necessary to bring the horn into operative relation with respect to the actuator so that a button (if desired) can be used to pull the draft device *r* when the button is pushed and the horn is 100 operated.

What I claim is:

1. In a device of the character described, the combination of a fan support, a bearing carried thereby, a fan and fan pulley rotatably supported by said bearing, a diaphragm-carrying arm supported on said 110

bearing, a diaphragm actuator secured to one of said rotating members so as to rotate therewith, a diaphragm-holding shell pivoted to the said diaphragm-carrying arm, a 5 diaphragm carried thereby, a spring for spacing the diaphragm-holding shell between the diaphragm-carrying arm and the diaphragm-holding shell, and means for drawing the diaphragm into operative 10 engagement with the actuator against the force of said spring.

2. In a device of the character described, the combination of a fan support, a bearing carried thereby, a fan and fan pulley rotatably mounted on said bearing, a dia- 15 phragm actuator secured to one of said rotating parts to rotate therewith, an arm secured to said bearing and extending in a general radial direction, a diaphragm-holding shell provided with a rearwardly ex- 20 tending lug pivoted to said arm, a dia- phragm carried by said shell and normally tending away from said diaphragm-carry- 25 ing arm and diaphragm actuator, and means for drawing the diaphragm into operative contact with the diaphragm actuator.

In testimony whereof, I sign this specification.

CHARLES G. TROSIEN.
